OF NEW YORK, N. Y.

VALVE MANIFOLD.

Application filed October 21, 1926. Serial No. 143,289.

This invention relates to valve manifolds, and more particularly concerns a valve manifold for use in connection with refrigeration systems.

5 In one general type of modern refrigeration systems, it is the practice to subject a suitable refrigerant to a continuous cycle of operations, the refrigerant being successively compressed, liquefied by cooling in a condenser, passed through a suitable expansion valve into a heat absorbing unit where it is gasified and returned again to be compressed. The pump or compressor used for compressing the gasified refrigerant is usually of the type in which a suitable fluid such as oil is used to maintain the various joints between the moved parts thereof effectively sealed.

10 In the operation of a system of this kind, it is necessary at times to charge the system with the required quantity of refrigerant, to add a small amount of refrigerant to the system to take the place of that lost through leakage, and to withdraw the refrigerant from the system when not in use. It is also necessary to add a small quantity of sealing fluid to the system to seal the various joints and connections thereof, particularly those between the moving elements of the compressor.

15 With the above and other considerations in mind, it is proposed in accordance with the present invention to provide a valve manifold for use in connection with refrigeration systems for permitting the refrigerant to be introduced into and drawn off from a refrigerating system, as well as to permit the introduction of a sealing fluid into the system.

20 It is a further object of the present invention to provide a manifold of this type which is compact, rugged and easily operated, and which is capable of performing the operations stated with substantially no loss of the liquids or gases handled.

25 It is a still further object of the present invention to provide a manifold of this type which may be used to relieve the load normally carried by the compressor by means of by-passing a portion of the compressed refrigerant through this manifold and returning it to the compressor.

30 It is a still further object of the present

invention to provide a manifold of the character described which is simple in construction and which can be readily and inexpensively manufactured without the use of complicated special machinery.

Other objects, advantages and characteristic features of the present invention will become apparent as the description thereof progresses.

In describing the invention in detail, references will be made to the accompanying drawing, in which;

Figure 1 is a plan view of the valve manifold of the present invention;

Figure 2 is a sectional view taken along the line 2—2 of Figure 1, and viewed in the direction of the arrows; and

Figure 3 is a sectional view taken along the line 3—3 of Figure 1 and viewed in the direction of the arrows.

The manifold of the present invention comprises, in general, a pair of parallel horizontal tubes or passages connected by a cross passageway, the various passages being provided with suitably arranged valves to control the flow of the refrigerant through the tubes and to control the communication between the cross passage and the tubes.

Referring to the drawings, two horizontal tubes, 1 and 2, are provided, being connected by a web 3 integrally formed therewith and having an enlarged portion 4 therein which is drilled out to form a cross passage 5 as shown in Figure 3. The web 3 is preferably provided with a suitable opening 6 to facilitate the attachment of the manifold to a suitable base or support on the refrigerating machine in connection with which it is to be used. The tubes 1 and 2 are suitably threaded at their ends, as shown, for the reception of unions or other suitable pipe connections, and are provided respectively with the valves A and B which control the flow of refrigerant therethrough. Two similar valves C and D are provided to control the communication between the passages in the tubes 1 and 2 and the cross passage 5.

100 As the valves A, B, C and D are substantially identical, only one of these valves will be described in detail, like reference characters being used to designate corresponding elements of the various valves. As shown in Figure 2, each of the passages in the tubes

1 and 2 has a horizontal portion 7 communicating with two short vertical passages 8 and 9. The upper end of each of the passages 8 and 9 opens into an enlarged valve chamber 10, the chamber of each of the valves A and B communicating through an angular passage 11 with a second horizontal passage 12, while the chamber 10 of each of the valves C and D communicates with 10 the cross passage 5.

The valve mechanism proper may take any suitable form, but in the embodiment shown herein comprises a sleeve member 13 screw threadedly secured to the upper end 15 of the walls 14 of the valve chamber 10 as shown, and carrying the valve stem 15. The valve stem 15 has a screw threaded engagement at 16 with the inner bore of the sleeve 13 and a suitable packing substance 17, such 20 as oiled wicking, is compressed between the upper portion of the stem 15 and the enlarged bore of the upper portion of the sleeve 13 by means of the packing nut 18. The upper end of the valve stem 15 is preferably slotted or otherwise formed for the 25 reception of a tool for operating the valve, and the upper end of the sleeve 13 is preferably closed by a plug 19, screw-threadedly engaging this sleeve, a washer 20 being preferably provided to insure a gas tight joint.

Integral with or suitably secured to the lower end of the valve stem 15 is a tapered plug 21. This plug is adapted, when the valve is closed and the stem 15 is in its lowered position, to engage and tightly close the upper end of the vertical passage 9, and when the valve stem 15 is in its open or upper position, as shown, to engage and tightly close the opening at the lower end 40 of the sleeve 13. The valves A and B are normally maintained in their open positions as shown, and when in this position the engagement of the plug 21 with the lower end of the sleeve 13 prevents the entrance of the 45 refrigerant into the inner bore of this sleeve and thereby avoids the corrosion of the moving parts and the packing of the valve by the refrigerant. The valves C and D are normally in their closed positions, and when 50 closed the refrigerant does not enter the valve chamber 10 and hence does not come into contact with the valve packing or the movable parts of the mechanism. It will be seen that the construction of these valves is such that the operating mechanism and packing thereof is exposed to the refrigerant only 55 while the valves are being moved from one position to another, and because of this construction and arrangement, the life of the valves is greatly prolonged.

The cross passage 5 comprises a plurality of angularly disposed passages which are formed by drilling away the metal of the enlarged portion 4 of the web 3 by means 60 of drills inserted through the openings in

the upper ends of the valve chambers 10. In a like manner, the angular passages 11 in the valves A and B are formed by means of drills inserted through the valve chambers 10 of these valves. In this manner, the various passages through the manifold may be readily and quickly formed with the use of ordinary drilling apparatus and it is therefore unnecessary to use complicated casting operations in the manufacture of the 70 valve manifold.

As shown in Figure 3, the cross passage 5 communicates with the valve chambers 10 of the valves C and D and also communicates with a feed pipe 22 provided with a cap 23 threaded to the outer end thereof. The feed pipe 22 preferably extends outwardly from the body of the manifold and is provided with a screw threaded outer end, adapted for suitable connection to a pipe 80 through which the refrigerant or the sealing fluid may be introduced into or withdrawn 85 from the system.

In the application of the valve manifold of the present invention to a refrigerating system, the passages through the tubes 1 and 2 may be connected to be included in the line of flow of the refrigerant at any suitable point where it may be desired to introduce or withdraw the refrigerant or the 90 sealing fluid to or from the system. For the purpose of illustration, it will be assumed that the passage through the tube 2 is connected in the gas line, that is, the pipe leading the refrigerant in gaseous form from the heat absorbing unit to the intake port of the compressor, while the passage through the tube 1 is connected in communication with the liquid line, that is, the pipe conducting the refrigerant in liquid form from 95 the outlet of the condenser to the expansion valve. The flow of liquid and gas through the passages in the tubes 1 and 2 is preferably in the direction indicated by the arrows in Figure 1. To obtain this direction 100 of flow the right hand end of the tube 1, as viewed in Figure 1, is connected with the exhaust end of the condenser and the left hand end thereof is connected with the expansion valve, while the right hand end of 105 the tube 2 is connected to the intake of the compressor and the left hand end thereof is connected to the exhaust end of the heat absorbing unit.

In the operation of the valve manifold of 110 the present invention, the valves A and B are normally open, while the valves C and D are normally in their closed positions. When it is desired to introduce a quantity of the refrigerant into the system, a pipe leading 115 to a tank or other container filled with the refrigerant is connected to the feed pipe 22 of the manifold. The valve B is then closed and the valve D gradually opened, thus permitting the flow of the refrigerant into the 120

gas line of the system. The refrigerant is usually carried in drums in which it is compressed in liquid form, and it therefore flows into the system under pressure, expanding 5 through the valve D and becoming gasified. From the tube 2, the refrigerant is drawn in gaseous form through the compressor and is pumped through the entire system. When the required amount of refrigerant has been 10 drawn into the system, the valve D is closed, the valve B opened and the drum or other supply is disconnected from the feed pipe 22, the cap 23 being replaced thereon. The sealing fluid may be introduced through the 15 feed pipe 22 and passage in the tube 2 in the same manner as that described in connection with the introduction of the refrigerant.

When it is desired to withdraw the refrigerant from the system, the cap 23 is removed 20 from the pipe 22 and a suitable discharge pipe is connected thereto. The valve A is now closed and the valve C opened, and the refrigerant, which at this point in the system is in liquid form and under high 25 pressure, passes out through the cross passage 5 and is discharged into a suitable container. The compressor may be operated to completely exhaust the refrigerant from the system, if desired. The valve C is then 30 closed, and the discharge pipe may be removed from the pipe 22.

It is often found in starting a new refrigerating system for the first time, that the compressor and the motor or other prime 35 mover for operating the same are considerably over-loaded, due, probably, to the tight fit of the bearings and other moving parts thereof. In this case, it is desirable to relieve the load on the compressor for a short 40 time in order to enable the compressor and motor to operate at a reasonable speed until the bearings thereof are properly run in. By the use of the manifold of the present invention, the load on the compressor may 45 be very easily relieved by slightly opening both of the valves C and D, and thus permitting a small amount of the compressed and liquefied refrigerant to expand through the cross passage 5 into the gas line, thus in effect, shunting or by-passing the refrigerant 50 through the compressor and thereby greatly decreasing the load thereon.

The valve manifold of the present invention presents many advantageous features of 55 construction and operation. The manifold is very compact and hence occupies little space in the system, which feature is extremely desirable in the domestic refrigeration systems now in use. Due to its novel construction, the manifold of the present invention 60 may be connected in the pipe line of a refrigerating system without materially complicating the arrangement thereof, all of the pipe connections to the manifold being 65 in the same plane. Also, the valves of the

manifold are enclosed under the plugs 19 and hence are not likely to be carelessly operated by unauthorized persons.

Although the manifold of the present invention has been described in a rather specific manner and in connection with one specific construction, it should be clearly understood that the invention is not limited to the exact details of construction shown, and that certain modifications, changes and additions 75 may be made thereto without departing from the scope of the invention as defined by the appended claims.

I claim:

1. In a valve manifold, a pair of parallel 80 straight tubes having independent passages therethrough, a web connecting said tubes, an enlarged portion in said web having a cross passage therein communicating with the passages in said tubes, valves for controlling the passages through said tubes and valves for controlling the communication between said tubes and said cross passage.

2. In a valve manifold, a pair of parallel 90 tubes having passages therethrough, an integral web connecting said tubes and having an opening therein to permit the manifold to be secured to a support, an enlarged portion in said web having a cross passage 95 therethrough communicating with said passages in said tubes, a feed pipe communicating with said cross passage and extending outwardly from said manifold, valves for controlling the passages through said 100 tubes, and further valves for controlling the communication between said cross passage and the passages in each of said tubes.

3. In a valve manifold, a pair of separate 105 parallel passages connected by a cross passage, valves in each of said passages for controlling fluid flow therethrough, valves for controlling the communication between each of said parallel passages and said cross passage and a feed pipe communicating with 110 said cross passage.

4. In a valve manifold, a pair of tubular members having independent passages extending from end to end thereof, the opposite ends of each of said passages lying in 115 the same plane, a cross passage connecting said parallel passages, valves for controlling fluid flow through said parallel passages, and valves for controlling the communication between each of said parallel 120 passages and said cross passage.

5. In a valve manifold, a pair of parallel 125 passages, a cross passage communicating with both of said parallel passages, a feed pipe communicating with said cross passage, valves for controlling the flow of fluid through said parallel passages and valves for controlling the communication between said cross passage and each of said parallel 130 passages, whereby said feed pipe may

connected with either of said parallel passages, said parallel passages may be connected in communication through said cross passage and the flow of fluid through said parallel passages may be controlled.

6. In a valve manifold, a pair of tubular members having parallel passages therein, an enlarged web connecting said members, a valve chamber having an open upper end integral with each of said members and communicating with the passages therein, and a cross passage through said web connecting said valve chambers, said cross passage comprising angularly disposed communicating cylindrical openings extending from said valve chambers at an angle such that the axes of said openings extend through the open upper ends of said chambers.

7. In a valve manifold, a pair of tubular members connected by an integral enlarged web, parallel passages in said members, valve chambers on said members communicating with the passages therein and having openings in their upper ends, a cross passage connecting said valve chambers comprising two angularly disposed straight passages communicating in said web, the axes

of said passages extending through the openings in the upper ends of said valve chambers, and valve mechanism adapted to engage the openings in said valve chambers and acting to control the communication between said chambers and said parallel passages in said tubular members.

8. In a valve manifold, a pair of tubular members connected by an integral web, parallel passages in said members, valve chambers on said members communicating with the passages therein and having openings in their upper ends, a cross passage connecting said valve chambers comprising two angularly disposed straight passages communicating in said web, the axes of said passages extending through the openings in the upper ends of said valve chambers, valve mechanisms engaging the openings in the upper ends of said valve chambers and acting to control the communication between said chambers and said parallel passages, and valves for controlling fluid flow through said parallel passages.

In testimony whereof I affix my signature.

ALFRED M. THOMSON.
